UNITED STATES PATENT OFFICE.

FRANK WINSTON CORLEY, OF RICHMOND, VIRGINIA.

CARRYING-CASE FOR TALKING-MACHINES.

1,278,440.

Specification of Letters Patent. Patented Sept. 16, 1918.

Application filed January 2, 1918. Serial No. 209,870.

To all whom it may concern:

Be it known that I, FRANK W. CORLEY, a citizen of the United States of America, residing at Richmond, in the county of Henrico and State of Virginia, have invented certain new and useful Improvements in Carrying-Cases for Talking-Machines, of which the following is a specification, reference being had therein to the accompanying drawing.

My invention relates to trunks or carrying cases for portable talking machines; and it has for its object the providing of a durable case in which the talking machine may be neatly packed, and transported without risk of damage to its various parts; and it has for its particular object the provision of a case adapted for hand transportation, in which the machine and its parts may be readily and securely packed, and from which they may be as readily removed.

In the drawings which accompany and form a part of this specification, and in which like numerals refer to like parts in the several views:—Figure I is a view, in perspective, of the carrying case or trunk with the talking machine packed in it, but with the tray of the case removed; Fig. II is a view, in perspective, of the tray of the carrying case with handle holders attached; and Fig. III is a cross section of the carrying case with the talking machine packed in it, and with the tray in place.

The body of the case, 1, is made of any suitable material of which carrying cases are made, and is furnished with clasps, a lock, corner reinforcements, hinges, etc., the hinges connecting to the body the lid 2.

The box of the machine is shown at 3, the record carrier at 4, the sound box arm at 5. The machine box is a neat fit from front to back of the carrying case, and is prevented from moving endwise therein by means of the rib 6. The swinging arm 5 is held against movement by means of the strap fastening 7 which is attached to the inside of the body 1.

The tray 8, see Figs. II and III, also is a neat and easy fit from front to back of the carrying case, and is prevented from moving endwise therein, when the case is closed, by means of the rib 9 secured inside the lid 2 of the case. Secured to the bottom and at each end of the tray are deep ribs 10, 10, which ribs, when the tray is in place

in the carrying case, support the said tray upon the top of the talking machine body 3. The tray is of sufficient depth, as shown in Fig. III, to neatly fill the space between the machine body and the inside of the lid of the carrying case. Also on the bottom of the tray 8, and between the ribs 10, 10, are two shallow ribs 11, 11. These ribs are of just sufficient depth to bear with a slight pressure upon the upper surface of the record carrier 4 of the talking machine. The bottom of the tray 8 is more or less elastic, and will give upward if the ribs 11, 11 tend to exert too much pressure upon the record carrier 4. In this way the record carrier is held against rotary motion, and without risk of injury, to the mechanism, during transportation.

The tray 8 I use for carrying the records 12, and other articles, such as needles, etc. On the right hand side of the tray the standing handle 12^a of the talking machine is supported in two loops or fastenings 13 and 14, the loop 13 being an adjustable strap, adapted to be tightened up on the handle to prevent slipping during transportation.

At the back of the lid of the carrying case, and between the rib 9 and the right hand end of the case, or that end which is opposite to the location of the tray 8, is a pocket 15 adapted to carry the sound box 16 of the talking machine, and in which the sound box is made secure by the adjustable strap 17.

It will be seen that the talking machine is secured against improper movement in the carrying case by means of the rib 6 and the tray 8, the latter being secured between the machine body and the lid of the carrying case, and also by the rib 9; that the mechanism of the machine is protected from jar or other disturbance by the bearing of the ribs 11, 11 of the record carrier; that the handle is secured in such a manner that it cannot become loose and injure other parts of the machine; that the sound box arm is secured against swinging, and in such a manner and position that if by accident it is freed from its fastening it cannot injure other delicate parts of the machine or be injured itself; and that the delicate sound box 16 is secured in such a position and in such a manner that it is effectively protected from injury.

Having described my invention, what I

claim and desire to protect by Letters Patent of the United States of America is—

A carrying case for talking machines including a receptacle for the talking machine, and a lid therefor, said receptacle having a stop to prevent endwise movement of the body of the machine, a tray for holding records having portions on the bottom thereof which with the tray form a distance piece between the machine body and the lid to prevent vertical motion of the former in the case, said tray also having portions adapted to bear on the record carrier of the machine to hold it against rotary motion,

and an adjustable fastening to hold the sound box arm against excessive lateral motion, and said lid having a stop to hold the tray against endwise motion, a pocket to receive the sound box of the machine, and a strap fastening arranged to hold the sound box securely in the pocket.

In testimony whereof I hereunto affix my signature in the presence of two witnesses.

FRANK WINSTON CORLEY.
